UNITED STATES PATENT OFFICE.

HENRY MCKINNIE, OF PITTSBURGH, PENNSYLVANIA.

DESIGN FOR A BENT-WIRE CLOTH-FASTENER.

56,880.

Specification for Design.

Patented Jan. 4, 1921.

Application filed June 21, 1920. Serial No. 390,674. Term of patent 14 years.

To all whom it may concern:

Be it known that I, HENRY MCKINNIE, a citizen of the United States, residing at Pittsburgh, in the county of Allegheny and the Commonwealth of Pennsylvania, have invented a new, original, and ornamental Design for a Bent-Wire Cloth-Fastener, of which the following is a specification, reference being had to the accompanying drawing, forming a part thereof.

Figure 1 is a plan view of the top looking downwardly thereon of the bent wire cloth fastener showing my design.

Fig. 2 is a plan view of the side looking directly thereon of the bent wire cloth fastener showing my design.

Fig. 3 is a plan view of the end looking directly thereat vertically of the bent wire cloth fastener showing my design.

I claim:

An ornamental design for a bent wire cloth fastener as shown.

HENRY MCKINNIE.

Witness:

JOSEPH BECK.
